UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

ROTARY FLUID-PRESSURE MOTOR.

Application filed September 26, 1918. Serial No. 255,787.

To all whom it may concern:

Be it known that I, MORRIS P. HOLMES, a citizen of the United States, residing at Claremont, in the county of Sullivan and State of New Hampshire, have invented certain new and useful Improvements in Rotary Fluid-Pressure Motors, of which the following is a full, clear, and exact specification.

10 This invention relates to rotary fluid pressure motors, more particularly, although not exclusively, to compressed air motors, and has for its general object to provide an improved motor of this type which is of simple, 15 inexpensive, and compact construction, which is capable of developing a relatively high power in proportion to its size and weight, which may be readily assembled and disassembled, and which is adapted to deliver the power generated in a convenient manner.

In said drawings,—

Fig. 1 is a plan view with the top of the casing broken away to show the rotors.

25 Fig. 2 is an end elevation.

Fig. 3 is a substantially central horizontal section.

Fig. 4 is a transverse vertical section taken substantially on the line 4—4, Fig. 3.

30 In the embodiment shown, the motor casting comprises a central section or portion 10 and two end sections or heads 11 and 12, respectively, said sections being held in assembled relationship by means of bolts or screws 13. The central section 10 is formed with two parallel, intersecting, cylindrical rotor chambers 14 (Fig. 4) to receive the rotors, designated as a whole by the numeral 15, which are mounted on shafts 16 journaled, as hereinafter more fully described, in the end sections or heads 11 and 12.

45 The two rotors 15 are provided with intermeshing blades or teeth each comprising two oppositely inclined spiral end portions connected at their inner ends by a short straight portion, as clearly shown in Fig. 1, thereby providing a double spiral or helical rotor couple of a well known general type.

50 For convenience in manufacture, each rotor is, in the present instance, composed of three connected sections, viz., two end sections 17 and 18 on which are formed, respectively, the oppositely inclined spiral tooth portions, and an intermediate section 19 on which are

formed the straight tooth portions, the outer ends of the latter registering with the inner ends of the respective spiral portions.

In rotors of this general type, as heretofore constructed, and comprising rotor sections having oppositely inclined teeth, it has been customary to key each of the rotor sections to the rotor shaft, and considerable difficulty has been encountered in bringing the ends of the teeth on the several sections 60 into exact register, as is essential to the proper operation of the device. It has usually been necessary, in assembling the rotor sections in this manner, after the angular positions of the sections have been fixed by 65 their keys, to cut away a greater or less amount at the inner end of one or another of the sections and move the same longitudinally toward the adjacent section, so that this longitudinal fitting may supply the necessary angular increment to bring the ends 70 of the teeth on the adjacent sections into exact circumferential register. This operation is not only a very delicate one, requiring great care and high skill, with a correspondingly high production expense, but results in an objectionable variation in the 75 length of the completed rotors.

In accordance with the present invention, these difficulties and objections are overcome 80 by keying only one of the rotor sections, herein the sections 18, to the shaft 16, and securing the remaining sections 17 and 19 thereto by means of longitudinally extending bolts 20, which not only serve to hold 85 the several sections in assembled relationship, but also to secure the sections 17 and 19 to the shaft 16 for rotation therewith by reason of their attachment to the section 18 which is, in turn, keyed to said shaft. With 90 this construction, the section 18 may first be keyed to the shaft and the other sections loosely assembled thereon and angularly adjusted relatively to the section 18 and to each other in order to bring the teeth thereon into 95 exact register. The several sections may thereupon be clamped in this position and holes drilled for the bolts 20, which are inserted and tightened, thereby producing an accurately formed rotor in a simple manner 100 and without shortening.

In order to reduce the total length of the motor to a minimum, as is desirable in the case of motors used in connection with certain classes of machinery, for example, in 110

mining machines, in which economy of space is an important consideration, the outer ends of the rotor sections 17 and 18 are recessed, as shown in Fig. 3, to receive projections or 5 bosses 21 formed on the end casing sections 11 and 12, said projections or bosses supporting the bearings for the shafts 16. As herein shown, the bearings 22 for one end 10 of each of the shafts are seated in sockets formed in the bosses 21 of the casing section 12, while the bearings 23 and 24 for the opposite ends of said shafts are located in bores extending through the bosses of the casing section 11, being retained therein by 15 rings or washers 25 suitably secured to the exterior of said casing section, as by cap screws. Preferably the bearings 22 and 24 will be of a suitable and approved roller type, while the bearing 23 may be a double 20 thrust ball bearing, secured by means of the usual nut or washer 26, for taking up the end thrust, if any, of the two shafts, said thrust being communicated from one shaft to the other by the engagement of the teeth 25 of the two rotors.

The preferred arrangement of the pressure fluid ports and passages is as follows. The end casing section or head 12 is formed adjacent its ends with two curved inlet 30 passages 27 (Figs. 2 and 3) arranged at opposite sides of a central gear chamber 28, hereinafter referred to, said inlet passages communicating, through an opening 29 (Fig. 2) in the inner wall of the casing 35 section 12, with a pressure chamber 30 (Fig. 4) formed in the bottom of the central casing section 10 beneath and between the rotor chambers 14, said pressure chamber having a port 31 through which pressure 40 fluid is admitted to the teeth of the rotors at a point substantially midway of the length of the latter, or opposite the straight toothed central rotor sections 19. One of the inlet passages 27 is provided at its upper 45 end with a fluid pressure inlet 32 (Fig. 2) which may be connected with any suitable source of fluid pressure supply through a pipe or conduit 33 (Fig. 1) controlled by the usual throttle valve (not shown). At 50 the upper end of the other inlet passage 27 is preferably provided an inwardly opening check valve 34 (Figs. 1 and 2) communicating with the atmosphere, whereby the inlet passages may be vented to prevent the 55 formation of vacuum therein due to overrunning of the motor by momentum after the throttle valve is closed.

The walls of the rotor chambers 14 surround the rotors 15 with a closely engaging 60 fit substantially throughout the peripheries of the latter, and the exhaust from the rotor teeth takes place at the ends of the rotors through annular exhaust cavities 35 (Fig. 3) formed in the end casing sections 11 and 12 65 and surrounding the bosses 21. The exhaust

cavities 35 communicate with exhaust chambers 36 (Fig. 4) formed in the top of the central casing section 10 above the rotor chambers, said exhaust chambers being provided with oil and dust traps 37 and discharging to the atmosphere through exhaust ports or openings 38 in the top wall of the casing. The arrangement described provides for a complete expansion of the motive fluid within the rotor chambers and a free exhaust 75 thereof after such expansion, thereby resulting in a high efficiency and the development of a high degree of power in proportion to the size of the motor.

The ends of the rotor shafts 16 extend 80 through the bearings 22 into the gear chamber 28 in the end casing section 12, and are there provided with transmission gears or pinions 39 (Fig. 3) splined or otherwise mounted thereon for rotation therewith but 85 movable longitudinally thereof, said pinions cooperating with a central transmission gear 40. It will be obvious that, since the rotors 15, and consequently the shafts 16, rotate in opposite directions, by engaging either one 90 or the other of the pinions 39 with the gear 40, the latter may be caused to rotate in either direction. Any suitable gear shifting mechanism may be employed for alternatively moving the pinions 39 longitudinally 95 of their shafts into and out of mesh with the gear 40. As herein shown, the pinions 39 are formed with grooved hubs 41 which are engaged by arms or levers 42 (Figs. 1 and 2) pivoted on studs 43 carried by a cover 100 plate 44 secured by screws 45 over an opening in the top of the casing section 12 and removable to afford access to the gear chamber 28. Said cover plate is preferably provided with openings through which 105 lubricant may be supplied to the gear chamber 28 and parts therein, said openings being closed by plugs 62. The levers 42 are formed with gear segments 46 which cooperate with a mutilated pinion 47 keyed to a stem 48 110 rotatably mounted in the cover plate 44 and provided outside the casing with an operating handle or knob 49. The arrangement is preferably such that, as the handle 49 is turned in one direction or the other from a 115 central neutral position in which both of the pinions 39 are out of mesh with the gear 40, one or the other of the arms 42 will be swung on its pivot to move the corresponding pinion into mesh with said gear, the remaining arm being locked against movement. This particular gear shifting mechanism 120 specifically forms no portion of the present invention, and, being of a well known type, is not illustrated in detail herein and requires no further description.

The gear 40 is formed with an elongated, tapering, sleeve-like hub 50 (Fig. 3) carried by a shaft 51 and on which is keyed the elongated hub 52 of the driving gear or 125

element 53 located outside the motor casing, and through which the power of the motor may be transmitted to the driven gear or element 54 of the mechanism to be actuated 5 thereby. The gear 53 is retained on the shaft 51, and the hub 52 thereof clamped in place on the hub 50 of the gear 40, by means of a nut 55 on the threaded end of said shaft, and said hub 52 is journaled in an anti-friction bearing 56 (preferably a roller bearing similar to the bearings 22 and 24) carried by a bushing 57 mounted in an opening in the wall of the casing section 12. The opening 66 in the gear 53 is preferably of a somewhat 10 greater diameter than the shaft 51 and is threaded, whereby a correspondingly threaded rod or bolt may be passed therethrough and into engagement with the end of the hub 50 to force said hub and gear apart in 15 20 disassembling. The inner end of the shaft 51 is in threaded engagement with a sleeve 58 rotatably mounted in an antifriction bearing 59 (preferably a double thrust ball bearing similar to the bearing 23) held by 25 a locking washer or ring 60 in an opening in a boss 61 projecting into the gear chamber 28 from the inner wall of the casing section 12, the inner end of said opening being closed by a cap 63 held in place by said bearing. 30 The sleeve 58 and hub 50 are connected by means of a pin 64 projecting from said hub and entering a longitudinal interior groove in said sleeve, thereby permitting longitudinal movement of said hub with respect to 35 said sleeve while maintaining the connection of said parts for rotation in unison. The shaft 51 is provided with a flange 65 against which the end of the hub 50 is clamped when the nut 55 is tightened. 40 The connections last described constitute the subject matter of a divisional application, filed Oct. 2, 1924, Serial No. 741,214. These connections permit an axial adjustment of the transmission gear 40 with its 45 connected driving gear 53 with respect to the bearing 59 and consequently with respect to the casing, this adjustment not being sufficient, however, to disturb or prevent the operative engagement of the pinions 39 with said gear 40. Such an adjustment is 50 extremely convenient in a motor of this character which is employed as the power element of a unitary machine, inasmuch as the positions of both the motor casing and 55 the driven gear in the machine frame are usually fixed in any given machine but, by reason of variations in workmanship, are likely to differ slightly in different machines, so that some adjustment to insure proper engagement of the driving and driven gears 60 is necessary or desirable, both in the initial setting of the parts and to compensate for subsequent wear. In the present machine, should adjustment of the driving gear 53 with respect to the driven gear 54 be re- quired, the nut 55 is loosened, and the shaft 51 is turned by means of a screw driver applied to the slotted end thereof, the gear 53, and consequently the hub 50 and sleeve 58, being held stationary, thereby by reason 70 of the threaded engagement of said shaft with the sleeve 58, adjusting said shaft with the gears 40 and 53 in an axial direction. Thereafter the nut 55 is tightened, said nut serving both to retain the gear 53 in place 75 on the hub of the gear 40 and to hold the shaft 51 against accidental turning in the sleeve 58 by clamping the flange 65 thereon against the hub 50. 80 In order to prevent the pressure fluid from the exhaust cavities 35 from reaching and passing through the bearings 22, 23, and 24 and the gear chamber 28, and thereby tending to blow the lubricant therefrom, the shafts 16 are provided intermediate their 85 bearings and the exhaust cavities, and within the bosses 21, with circumferential grooves 67 which communicate through ports 68 with axial passages 69 in said shafts which extend to the ends thereof at the exterior 90 of the casing. Exhaust air passing along the shafts from the exhaust cavities will encounter the grooves 67 before reaching the bearings, and thence will be discharged through the ports 68 and passages 69 to the 95 atmosphere. 100 While I have in this application specifically described one form which my invention may assume in practice, it will be understood that this form of the same has been shown for purposes of illustration and that the invention may be modified and embodied in various other forms without departing from its spirit or the scope of the appended claims. 105 What I claim as new and desire to secure by Letters Patent is: 110 1. In a fluid pressure motor, a casing having a rotor chamber, a pressure chamber below said rotor chamber and communicating therewith, an exhaust chamber above said rotor chamber and communicating therewith only through the ends thereof, an oil and dust trap in said exhaust chamber, and an exhaust port in the top of said casing leading from said exhaust chamber to the atmosphere. 115 2. In a fluid pressure motor, a casing having a rotor chamber, end closures for said casing having exhaust cavities communicating with said rotor chamber, a gear chamber formed on one of said end closures, and pressure fluid inlet passages extending around the exterior of said gear chamber and communicating with said rotor chamber. 120 3. In a fluid pressure motor, a casing having a plurality of rotor chambers, a pressure chamber below and between said rotor chambers, and end closures for said casing 125 130

having exhaust cavities communicating with said rotor chambers, one of said end closures having a gear chamber, and pressure fluid inlet passages extending around said gear 5 chamber and communicating with said pressure chamber in said casing.

4. In a fluid pressure motor, a casing comprising a central section and end sections secured to said central section, each of said 10 latter sections having rotor bearings, said central section having a rotor chamber and pressure and exhaust chambers, and one of said end sections having pressure and exhaust spaces communicating with said pressure and exhaust chambers, respectively.

5. In a fluid pressure motor, a casing comprising a central section and end sections secured to said central section, said central section having a rotor chamber and an exhaust 20 cavity, a rotor in said chamber, and rotor bearings disposed adjacent each of said end sections and at least one of said sections and the bearing adjacent thereto being removable to allow removal of said rotor and said 25 end sections having exhaust cavities communicating with the ends of said rotor chamber and with said exhaust cavity in said central section.

6. In a fluid pressure motor, a casing comprising a central section and end sections secured to said central section, each of said 30 latter sections having rotor bearings each accessible from the end in which they are disposed, said central section having a 35 plurality of rotor chambers, a pressure chamber below and between said rotor chambers, an exhaust chamber above said rotor chambers, and ports leading from said exhaust chamber to the atmosphere, and one 40 of said end sections having pressure and exhaust spaces communicating with said pressure and exhaust chambers, respectively.

7. In a fluid pressure motor, a casing comprising a central section, an end section secured to said central section, said central section having a rotor chamber and a pressure chamber and said end section having an exhaust cavity communicating with said 50 rotor chamber, a gear chamber, and fluid inlet passages extending around said gear chamber and communicating with said pressure chamber.

8. A fluid pressure motor comprising a casing and a rotor therein, said casing having a branched inlet passage leading to said 55 rotor, one of said branches being connected to a source of fluid pressure, the second having an inwardly opening check valve therein, and a branched exhaust connection in 60 said casing leading from the ends of the rotor to the atmosphere.

9. In a fluid pressure motor, a casing having a rotor chamber, exhaust connections leading from the ends of said rotor chamber, a gear chamber at one end of said rotor

chamber, and a plurality of fluid inlet passages extending around said chamber and communicating with said rotor chamber, one of said passages leading to a source of fluid pressure and another of said passages having an inwardly opening check valve communicating with the atmosphere. 70

10. In a fluid pressure motor, the combination with a casing having a substantially cylindrical rotor chamber, of a rotor 75 in said chamber having recessed ends, bearings for said rotor carried by the end walls of said chamber within the recessed ends of said rotor, and leakage connections between the bearings at opposite ends of the rotor 80 and the atmosphere.

11. In a fluid pressure motor, the combination with a casing comprising a central section and two end sections secured to said central section, said central section having 85 a rotor chamber and a pressure chamber communicating therewith, of a rotor in said rotor chamber having recessed ends, and bearings for said rotor carried by said end sections within the recessed ends of said 90 rotor, said bearings having leakage vents communicating with each other and with the atmosphere.

12. In a fluid pressure motor, the combination with a casing having a rotor chamber 95 provided with end walls, of a rotor in said chamber having recessed ends, the end walls of said rotor chamber being provided with bosses extending into the recessed ends of said rotor and with annular exhaust cavities surrounding said bosses, bearings for said rotor carried by said bosses, and means to prevent leakage from said exhaust cavities through said bearings.

13. In a fluid pressure motor, the combination with a casing having a rotor chamber, of a rotor in said chamber, a shaft on which said rotor is mounted, and a bearing for said shaft within the end wall of said chamber, said shaft having a circumferential groove between said chamber and said bearing and a longitudinal passage communicating with said groove and extending to the exterior of said casing. 105

14. In a fluid pressure motor, the combination with a casing having a rotor chamber provided with end walls, of a rotor in said chamber having recessed ends, a shaft on which said rotor is mounted, the end walls of said rotor chamber being provided with 110 bosses extending into the recessed ends of said rotor and with annular exhaust cavities surrounding said bosses, and bearings for said shaft within said bosses, said shaft having circumferential grooves between said 115 bearings and the inner ends of said bosses and a longitudinal passage communicating with said grooves and extending to the exterior of said casing.

15. In a fluid pressure motor, the combi- 120

nation with a shaft, of a multi-sectioned toothed rotor thereon comprising a section fixed to said shaft and one or more sections held in fixed relation with respect to said shaft only by a rigid connection to said first mentioned section, but fitting said shaft snugly.

16. In a fluid pressure motor, the combination with a shaft, of a multi-sectioned rotor thereon comprising a section having straight teeth and one or more sections provided with inclined spiral teeth, one of said sections being rigidly secured to said shaft and another secured to said last mentioned section, but not to said shaft, but being a snug fit therefor.

17. In a fluid pressure motor, the combination with a shaft, of a double spiral rotor thereon comprising a plurality of sections provided respectively with oppositely inclined spiral teeth, one of said sections being fixed to said shaft and another of said sections being loosely mounted on said shaft and rigidly secured to said first named section, said shaft having bearing portions at opposite sides of said rotor.

18. In a fluid pressure motor, the combination with a shaft, of a double spiral rotor thereon comprising a plurality of sections provided respectively with oppositely inclined spiral teeth, one of said sections being fixed to said shaft and another of said sections being loosely mounted on said shaft, and one or more bolts for rigidly securing said sections together, said shaft extending completely through said rotor and having journal portions adjacent opposite ends thereof.

19. The combination with a driven element, of a motor comprising a casing, motor elements within said casing, a driving element carried by said casing and operatively connected with said motor elements and with said driven element, and means whereby said driving element may be adjusted with respect to said casing and said driven element.

20. The combination with a driven element, of a motor comprising a casing, motor elements within said casing, a driving element operatively connected with said motor elements and with said driven element, a longitudinally adjustable shaft supported in said casing and by which said driving element is carried, and means for retaining said driving element on said shaft and for retaining said shaft in adjusted position.

21. The combination with a driven element, of a motor comprising a casing, motor elements within said casing, a driving element operatively connected with said motor elements and with said driven element, a bearing within said casing having a rotating member connected with said driving element for rotation therewith, said member and element being relatively longitudinally movable, and a shaft having threaded engagement with said rotating member whereby said shaft is longitudinally adjustable with respect to said member, said driving element being mounted on said shaft and longitudinally movable therewith.

22. The combination with a driven element, of a motor comprising a casing, motor elements within said casing, a driving element operatively connected with said motor elements and with said driven element, a bearing within said casing having a rotating member connected with said driving element for rotation therewith, said member and element being relatively longitudinally movable, a shaft having threaded engagement with said rotating member whereby said shaft is longitudinally adjustable with respect to said member, said driving element being mounted on said shaft and longitudinally movable therewith, and means for retaining said driving element on said shaft and for retaining said shaft in adjusted position.

23. The combination with a driven gear, of a motor comprising a casing, a rotor therein, a transmission gear operatively connected with said rotor and having a hub, a driving gear meshing with said driven gear and mounted on said hub for rotation therewith, a bearing within said casing, a sleeve journaled in said bearing and having a splined connection with said transmission gear, a shaft on which said transmission gear is rotatably mounted, said shaft having a collar engaging the end of the hub of said transmission gear and having threaded engagement with said sleeve whereby said shaft and the gears thereon are longitudinally adjustable and a nut on the end of said shaft and engaging said driving gear, whereby said driving gear is retained on said hub and said hub forced into engagement with the flange on said shaft to hold said shaft against turning in said sleeve.

In testimony whereof I affix my signature.
MORRIS P. HOLMES.
